UNITED STATES PATENT OFFICE.

WALLACE HIRAM CARTER, OF EAST MILTON, MASSACHUSETTS.

GRIPPING-LEVER.

SPECIFICATION forming part of Letters Patent No. 723,827, dated March 31, 1903.

Application filed July 15, 1902. Serial No. 115,712. (No model.)

To all whom it may concern:

Be it known that I, WALLACE HIRAM CARTER, a citizen of the United States, residing at East Milton, in the county of Norfolk and State of Massachusetts, have invented certain new and useful Improvements in Gripping-Levers; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to gripping-levers, and has for its object to provide a device of this class which is particularly simple in construction and easy and positive of operation.

A further object of my invention is to provide a lever for gripping hoop-iron, strap-iron, or wire for the purpose of stretching or drawing the same tight when used for box-straps or fencing and the like.

With these objects in view my invention 25 consists in the particular construction and arrangement of my lever.

My invention further consists in arranging a lever whereby the grip and strain are on the same plane and parallel with the pivotal 30 point of the two sections of the lever.

My invention further consists in certain other novel features and in combination of parts, which will be first fully described, and afterward specifically pointed out in the appended claims.

35 Referring to the accompanying drawings, Figure 1 is a front elevation of my invention. Fig. 2 is a side elevation of the same. Fig. 3 is a detail view of the upper section of the lever. Fig. 4 is a detail view of the lower section. Fig. 5 is a front elevation of the lever in an operative position. Fig. 6 is a side elevation of the lower section.

Like numerals of reference indicate the 45 same parts throughout the several figures, in which—

1 is the lever, composed of the upper section 2 and lower section 3.

40 4 indicates the handle, which is securely 50 bolted in the upper section between the sides 5.

6 indicates metal division-blocks, and 7 is

a metal strip which passes between said blocks and between the sides 5. 8 indicates the grooves in said sides and metal strip for 55 the reception of the hoop-iron or wire, and 9 indicates two bolt-holes, being in the same plane as the grooves 8.

The lower section 3 is composed of the side pieces or extensions 10, and the division-block 11 between the two, the whole being securely bolted together.

12 indicates the grooves in the side pieces for the reception of the hoop-iron or wire, and 13 indicates two elongated bolt-holes in 65 the side pieces.

Having thus described the several parts of my invention, its operation is as follows: The lower section is inserted between the sides of the upper section, as shown, and the bolts 14 70 are passed through the two. The lever is now ready for operation, and as the grooves in both sections are in the same horizontal plane the hoop-iron or wire is passed in. When the handle is moved in the direction 75 it is desired to stretch or pull the hoop-iron or wire, the elongated bolt-holes in the lower section allow the said section to tilt a trifle, as shown in Fig. 5, thereby carrying the grooves in the upper and lower sections out 80 of line, or rather carrying the plane of the grooves of the lower section obliquely across the plane of the grooves of the upper section, which causes the hoop-iron or wire to be gripped, and the more force that is exerted 85 on the handle the tighter and harder the hoop-iron or wire is held in the grooves.

It will be seen that the hoop-iron or wire while being pulled or stretched assists the bolts 14, taking the strain from them, as the 90 binding of the two sections is on the hoop-iron or wire, thereby making it possible to construct the lever much lighter than other devices for the same work. It will also be noticed that although the hoop-iron or wire is 95 gripped tightly the grip is of such a character that the material to be pulled will not stick in the grooves, but can be taken out of engagement just as soon as the power is off the handle.

100 By referring to Fig. 2 it will be seen that the hoop-iron or wire enters the groove in the lower section first. It will be also noticed that the center of the handle, gripping-line

of groove 8, and center of bottom edge 15 of lower section are in the same vertical plane, thereby preventing the lever from turning or twisting while in operation.

Having thus specifically described my invention, I wish it to be understood that the lower section may be constructed with three or more pieces or extensions 10, and the upper section may have two or more metal strips 7, so as to increase the number of gripping or binding points. Furthermore, I do not wish to be understood as limiting myself to the exact construction herein set forth, but consider myself clearly entitled to all such changes and modifications in form and construction as fall within the limit and scope of my invention as defined by the following claims.

What I claim as new, and desire to secure by Letters Patent of the United States, is—

1. In a gripping-lever, the combination of two levers having gripping-slots lying normally in a transverse plane, and pivotal means lying in the plane of the slots consisting of fixed bolts in one lever and elongated slots in the other through which the bolts pass.

2. In a gripping-lever, the combination of

two sections loosely pivoted together, means in said sections for gripping material, the gripping means in said lower section being 30 adapted to lie in a plane obliquely across the plane of the gripping means in the upper section, when the lever is in operation.

3. In a gripping-lever, the combination of two sections, pivoted together, gripping 35 means in said sections which are in the same plane with each other when the lever is at rest, and which are obliquely located when in operation.

4. In a gripping-lever, the combination of 40 an upper section, a lower section secured thereto, said sections being provided with slots normally in alinement for the reception of the material to be gripped, and means connecting the sections and allowing said slots 45 to pass out of alinement by a lateral movement.

In testimony whereof I affix my signature in presence of two witnesses.

WALLACE HIRAM CARTER.
